UNITED STATES PATENT OFFICE.

DANIEL VANZILE, OF VREDENBURGH, ALABAMA.

STEAM-FEED VALVE.

1,348,608.

Specification of Letters Patent. Patented Aug. 3, 1920.

Application filed May 28, 1919. Serial No. 300,353.

To all whom it may concern:

Be it known that I, DANIEL VANZILE, a citizen of the United States, residing at Vredenburgh, Alabama, have invented a certain new and useful Improvement in Steam-Feed Valves, of which the following is a full, clear, and exact description, such as will enable others skilled in the art to which it appertains to make and use the same, reference being had to the accompanying drawings, forming part of this specification.

My invention relates to a steam feed or control valve, and while particularly designed for use in connection with the steam feed cylinders of saw mills, can be advantageously utilized wherever it is desired to positively control the feed of fluid pressure to a cylinder or the like and to permit the exhaust of said fluid pressure from said cylinder.

The valve herein illustrated and described is an improvement on the steam feed valve disclosed in my copending patent application on steam feed valve control mechanism, filed March 24, 1919, Serial Number 284,713.

In my application aforesaid, the valve proper is secured to the valve stem by one or more nuts which are arranged on threaded portions of the valve stem and bear directly on top of the valve body. This construction necessitates the formation of a thread on the valve stem and to produce this thread it is necessary to reduce the diameter of the valve stem above said thread. Further, after continued use, the nuts which are seated on the threaded portion of the stem and which retain the valve in fixed position on said stem, frequently become loose and in order to tighten them the upper part or head of the valve must be removed.

It is the principal object of my present invention to overcome the objectionable features just noted and provide a relatively simple construction which will be effective in retaining the valve in proper position upon the stem and said retaining means being locked to the valve stem by a nut or the like which is located on the exterior of the valve housing and in which position it is readily accessible.

With the foregoing and other objects in view, my invention consists in certain novel features of construction and arrangement

of parts, hereinafter more fully described and claimed, and illustrated in the accompanying drawings, in which—

Figure 1 is a vertical section taken through the center of a valve of my improved construction.

Fig. 2 is a perspective view of the valve stem.

Fig. 3 is a perspective view of the sleeve which is applied to the valve stem for retaining the valve in proper operative position thereupon.

Referring by numerals to the accompanying drawings, 10 designates the body or housing of the valve in which is formed a vertically disposed cylindrical valve chamber 11, the upper end of which is closed by a removable head or plate 12 in the center of which latter is arranged a gland nut 13.

Secured to the lower end of the valve housing 10 is a tubular elbow 14 which serves as an outlet for the exhaust steam or fluid pressure passing through the valve and located in the lower portion of said elbow is a gland nut 15, the same being in direct vertical alinement with gland 13.

Formed through the wall of valve housing 10 is a steam or fluid pressure inlet port 16 and secured to said housing and communicating with said port is a steam or fluid pressure supply pipe 17. Formed through the wall of housing 10 and oppositely disposed with respect to inlet port 16 is a port 18 and connected to the valve housing and communicating with this port is a tubular connection 19 which leads to the steam cylinder or other structure to which steam or fluid pressure is to be intermittently supplied.

The stem of my improved valve comprises an elongated rod 20, preferably having the same diameter throughout its length, and rigidly fixed on said stem near its center is a collar or flange 21. Positioned on this valve stem immediately above the collar or flange 21 is a cylindrical valve 22, the diameter of which is such that it slides freely through the chamber 11 and formed in the outer face or periphery of said valve is an annular groove 23, which serves to establish communication between ports 16 and 18.

To retain the valve 22 in proper position on the valve stem, a short tubular member or sleeve 24 is positioned on the upper portion of the valve stem with its lower end

bearing directly on top of the valve 22. This sleeve is arranged to slide freely through gland nut 13 and its upper end terminates adjacent to the threaded upper 5 end 25 of valve stem 20. Seated on this threaded upper end of the valve stem is a nut 26 which, when tightened, bears directly on top of the sleeve 24 and the downward pressure imparted to the latter by said nut 10 is transmitted to valve body 22 and the latter is firmly held in proper position upon the valve stem with its lower end against the flange or collar 21.

Screw-seated on the upper end of threaded 15 portion 25 and above nut 26 is a nut 27 with which is formed integral a loop or eye 28 and attached to the latter is one end of a cable 29 which is utilized in raising the valve stem and parts carried thereby. The 20 lower end of the valve stem is threaded as designated by 30 and seated upon said threaded end is a nut 31 provided with an integrally formed eye 32 and to which latter is secured one end of a cable 33 which is utilized 25 for pulling the valve stem and parts carried thereby downwardly. The cables 29 and 33 are connected to suitable valve operating mechanism, preferably of the type disclosed in my hereinbefore mentioned co-pending patent application.

When valve 22 is in its lowermost position, as illustrated in Fig. 1, the annular groove or recess 23 establishes communication between ports 16 and 18 and thus steam 35 passes from supply pipe 17 through the valve and thence through pipe 19 to the steam feed cylinder of a saw mill or the like and when the steam supplied by the valve has done its work, the operating mechanism 40 to which cable 29 is connected is actuated, thereby raising the valve stem and valve 22 is carried into the upper portion of chamber 11, thereby cutting off communication between the ports 16 and 18 but opening 45 the latter to that portion of the chamber

below the valve 22 and as a result steam or fluid pressure will exhaust through port 18 and after passing downwardly through the chamber 11 will exhaust through outlet 14.

In the event that valve 22 should become 50 loose in service, nut 26 is tightened to force sleeve 24 downward, thereby maintaining valve 22 in rigid position upon the valve stem, and as nut 26 is readily accessible such adjustment or take-up can be very easily 55 and quickly accomplished.

A valve of my improved construction is comparatively simple, can be very readily adjusted to take up wear or lost motion, and can be very easily and cheaply manufactured.

It will be readily understood that minor changes in the size, form and construction of the various parts of my improved valve can be made and substituted for those herein shown and described, without departing from the spirit of my invention, the scope of which is set forth in the appended claim.

What I claim is:

In a valve of the class described, a housing provided with ports and a valve chamber, a valve arranged for operation within said valve chamber for communicating with said ports, a valve stem passing through said valve and having bearings in the upper 75 and lower portions of the housing, the ends of the stem being screw-threaded, a shoulder on said valve stem against which the valve engages, a sleeve on the upper portion of the valve stem, which sleeve bears against the valve and is arranged to slide through the bearing in the upper portion of the housing, a nut for locking said sleeve and valve upon the stem, and a nut provided with an eye or loop on each end of the stem to which 80 85 may be secured operating cables.

In testimony whereof I hereunto affix my signature this 22nd day of May, 1919.

DANIEL VANZILE.
